Filed Oct. 16, 1922

INVENTOR:

Edmund Vorbroker,

BY *John Elias Jones,*

ATTORNEY.

UNITED STATES PATENT OFFICE.

EDMUND VORBROKER, OF CINCINNATI, OHIO.

DESIGN FOR A CASING FOR AN ELECTRIC WAY AND STOP SIGNAL DEVICE FOR AUTOMOBILES AND OTHER VEHICLES.

Application filed October 16, 1922. Serial No. 3,991. Term of patent 3½ years.

To all whom it may concern:

Be it known that I, EDMUND VORBROKER, a citizen of the United States of America, residing at Cincinnati, in the county of Hamilton and State of Ohio, have invented a new, original, and ornamental Design for Casing for Electric Way and Stop Signal Devices for Automobiles and Other Vehicles, of which the following is a specification, reference being had to the accompany-

ing drawing, forming a part thereof.

The view presented is a semi-perspective front elevation of the signal device that embodies my design herein and shows the essential, salient features thereof.

I claim:

The ornamental design for casing for an electric way and stop signal device for automobiles and other vehicles, as shown.

EDMUND VORBROKER.
